UNITED STATES PATENT OFFICE.

WILLIAM M. HALL, OF NEW YORK, N. Y.; FRANCIS M. HALL ADMINISTRATOR OF SAID
WILLIAM M. HALL, DECEASED.

SANITARY CAN AND SEAL.

Application filed January 10, 1924, Serial No. 685,413. Renewed August 1, 1925.

To all whom it may concern:

Be it known that I, WILLIAM M. HALL, a citizen of the United States, and a resident of the city of New York, borough of Manhattan, in the county and State of New York, have invented a new and Improved Sanitary Can and Seal, of which the following is a full, clear, and exact description.

This invention relates to containers and particularly to tin cans and sealing means therefor and has for an object to provide an improved structure which may be quickly, economically and easily sealed and unsealed.

Another object of the invention is to provide a seal for a can or other container in which co-acting folding portions are provided, not only acting as a seam structure, but as means for containing sealing material.

A still further object of the invention is to provide a seal for a tin can in which an annular groove is provided in the can and an annular depending co-acting portion is provided on the lid fitting into the groove, the groove structure and the depending structure on the lid being capable of bending into a very close relationship.

A further object of the invention is to provide an effective seal which may not only be quickly sealed but may be quickly and easily unsealed without the use of a conventional can opener or any other object designed especially for can opening.

A still further object is to provide a seal for a can which does not use solder and which may be opened by an instrument or by a blow against an object without injuring the person opening the can.

In the accompanying drawing—

Figure 1 is a transverse sectional view through a lid disclosing certain features of the invention.

Figure 2 is a transverse sectional view through a tin can disclosing certain features of the invention.

Figure 3 is a transverse sectional view through the upper part of the can shown in Figure 2 with the lid applied.

Figure 4 is an enlarged fragmentary sectional view through the seam and part of the can and lid illustrating how the parts are assembled and how the sealing material is held in place.

Figure 5 is a view similar to Figure 4 but showing the parts clamped together and

also illustrating how a tool may be used 55 for opening the seal.

Referring to the accompanying drawing by numerals, 1 indicates a can or other container which at the upper end is bent down for forming a trough-shaped structure 2, 60 said trough-shaped structure being formed with an annular flange 3. Co-acting with the trough-shaped structure 2 is a depending annular bead structure 4 extending from the periphery of the lid 5. The bead structure 4 is adapted to be opened somewhat as well as the trough-shaped structure 2 though it is sufficiently pressed together at the lower edge to freely enter the trough-shaped structure 2 as illustrated in Figure 4. 70 Preferably soldering wax or other suitable easily melting soldering medium 6 is placed in the trough-shaped structure 2 when the lid is to be sealed and then the lid placed in position as shown in Figure 4. When 75 the lid is in this position, the flange 7 extending from the bead 4 overlaps the flange 3 while the curved wall 8 of the lid 5 fits inside of the curved section 9 of the can 1. From Figures 1 and 3, it will be seen that 80 the lid is provided with a depending central part or rather the bead 4 is spaced above the bottom of the lid so that the lid will project further into the can 1 than the bead overlaps the same. This is very desirable 85 and permits a ready curving of the top of the can body when the parts are pressed together as indicated in Figure 5.

After the parts have all been assembled as shown in Figure 4, a suitable instrument 90 is caused to act upon the parts for squeezing them to the position shown in Figure 5. The parts may be heated until the wax or other sealing medium 6 is melted before this squeezing operation or the melting may be 95 done by the squeezing apparatus if the same is heated. By this construction and arrangement, it will be noted that an interlocking seam of metal is provided and in addition a sealing medium is used which presents an 100 absolute seal against the entrance of air or other foreign matter. By providing the flange 7, an instrument 10 may be used for opening the seal, this instrument being a screw driver or knife usually.

The cover may be removed by striking with the object 10 so that the object will engage the flange on the under side thereof.

This will liberate the cover by springing it free from its jacket and at the same time break the sealing substance. This construction of seal permits the lid to be used a 5 second time or in fact for a number of times so that when goods are packed in cans at the factory and the cans properly sealed, they may be opened in the home and used for private canning as the opening of the 10 lid will not mutilate the same. It will be noted that the body of the can may be of any desired size and shape also while the trough at the upper part is so shaped that the substance used in sealing cannot flow 15 into the contents of the can while the contents are being heated preparatory to applying the cover. This arrangement of trough permits the wax or other sealing medium to be readily placed in position and then permits the lid to be also readily placed in position and squeezed transversely of the can body until the parts appear substantially as shown in Figure 5. In order to secure the 20 best results, the bottom or body of the lid drops down or rather extends down below the annular bead structure 4 whereby the parts may be properly squeezed together and the upper end of the can curved at the same 25 time.

30 What I claim is:—

1. A can, comprising a body having an annular exterior trough surrounding its upper end, and a lid having an annular exterior trough provided with a downwardly 35 extending flange on its outer wall, the trough

of the lid extending into the trough of the body with the outer wall of the trough of the body extending between the outer wall of the trough of the lid and its flange, the body and lid and their troughs being adapted to be 40 pressed into engagement with the flange of the lid overlapping the outer wall of the trough of the body.

2. A can or container and lid therefor, comprising a can body formed with an annular trough-shaped structure extending outwardly and downwardly from the upper edge of said body and a lid body, the floor of the lid body being of less diameter than the interior of said can body whereby the lid body may be inserted into the can body for the depth of the lid, said depth being slightly greater than the distance that said trough-shaped structure extends downwardly, a sealing medium in the trough-shaped structure, said lid body being also formed with a trough-shaped structure extending outwardly from its upper edge and having a flange extending downwardly from its outer wall, said trough structure being adapted to extend into the trough-shaped structure of the can body and said flange being adapted to overlap the outer edge of said trough-shaped structure of the body, said flange and trough-shaped structures being 50 nested whereby they may be collapsed simultaneously and interlocked to seal the lid body in position on the can body.

55 WILLIAM M. HALL.
